FISH LURE

Ewell J. Harris, Rte. 3, Box 135A,
Adrian, Mich. 49221

Continuation-in-part of design application Ser. No.
23,537, June 19, 1970. This application Mar. 16,
1972, Ser. No. 235,475

Term of patent 14 years

Int. Cl. D22—05

U.S. Cl. D22—28

FIG. 1.

FIG. 2.

FIG. 1 is a top plan view of a fish lure showing my new design, the bottom view being substantially similar to FIG. 2.

FIG. 2 is a side elevational view of the fish lure shown in FIG. 1; the side opposite is similar but opposite hand.

The present application is a continuation-in-part of application Ser. No. D. 23,537, filed June 19, 1970 and now abandoned.

I claim:

The ornamental design for a fish lure, substantially as shown.
